RAILWAY SIGNALING

Leslie R. Allison, Forest Hills, Pa., assignor to The Union Switch & Signal Company, Swissvale, Pa., a corporation of Pennsylvania

Application March 14, 1936, Serial No. 68,807

27 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of four track sections in the rear of an occupied section. Each distinctive control is effective to cause a corresponding aspect of the associated wayside signal, whereby there is produced a four-block, five-indication system of signaling.

Another feature of my invention is the provision of novel and improved apparatus for establishing a distinctive control for each of three track sections in rear of an occupied section for controlling the associated wayside signal to produce a three-block, four-indication signaling system.

20 The system shown in this application is an improvement on the systems shown in an application of Howard A. Thompson, Serial No. 692,155, filed October 4, 1933, for Railway traffic controlling apparatus; in an application of Henry S. 25 Young, Serial No. 66,002, filed February 27, 1936, for Railway signaling; in United States Patent No. 2,062,055, issued November 24, 1936, to Ralph R. Kemmerer, for Railway signaling; in an application of George R. Pflasterer, Serial No. 30 68,497, filed March 12, 1936, for Railway signaling; and in an application of Paul H. Crago, Serial No. 631,041, filed August 30, 1932, for Remote control systems.

I will describe several forms of apparatus embodying my invention, and will then point out the novel features thereof in claims.

In the accompanying drawings, Figs. 1A, 1B, and 1C are diagrammatic views which, when placed end to end in the order named, illustrate one form of four-block, five-indication, signaling system embodying my invention. Figs. 2A and 2B are diagrammatic views which, when placed end to end in the order named, illustrate one form of three-block, four-indication signaling system embodying my invention. Figs. 3, 4, 5, 6, 45 7, and 8 are diagrammatic views illustrating modifications of a portion of the apparatus shown in Figs. 2A and 2B, and each also embodies my invention. Fig. 9 is a diagrammatic 50 view illustrating a modification of a portion of the apparatus shown in Fig. 8 and also embodying my invention.

Similar reference characters refer to similar parts in each of the several views.

55 Referring first to Figs. 1A, 1B, and 1C, the ref-

erence characters 15 and 16 designate the rails of a stretch of railway track along which traffic normally moves in the direction indicated by the arrows. The rails 15 and 16 are divided by insulated joints 17 into track sections V—W, W—X, X—Y, and Y—Z. Each track section is divided into at least two subsections 1T, 2T, 3T, 4T, etc.

Each subsection is provided with a track battery 18 connected across the rails at one end of the subsection and with a track relay, designated 10 by the reference character TR with a prefix the same as the numerical prefix of the associated subsection, connected across the rails at the other end of the subsection.

For governing the passage of trains along the 15 stretch, each track section is provided with a wayside signal designated by a suitable distinguishing reference character.

These signals may take any one of several forms such as searchlight, color light, semaphore, 20 or position light. As here shown, each signal is of the color light type and includes an upper indication unit U and a lower indication unit L. Each unit U and each unit L includes a red lamp R and a yellow lamp Y as well as a green 25 lamp G.

For controlling the signals, each section is provided with a polarized direct current relay and with a neutral direct current relay designated by the reference characters H and J, respectively, each with a prefix the same as the reference character of the associated signal.

For controlling the relays, H and J, each section is provided with a line circuit which includes a pair of line wires each of which includes a 35 front contact of each of the associated track relays. As will be explained more in detail hereinafter, the line circuits, at times, are supplied with direct current only of one polarity or the other and at other times are supplied with alternating current simultaneously with direct current.

Each polarized relay H is directly connected to the associated line circuit. Each neutral relay J is connected to the associated line circuit 45 through an asymmetric unit, a transformer, and a condenser designated by the reference characters Q, M, and F, respectively, each with a prefix the same as the reference character of the associated signal. The relatively high impedance of the windings of the relays H will prevent the flow of alternating current in these relays and the condensers F, together with the transformers M will prevent the flow of the direct current from the line circuit in the wind- 50 55

ings of the relays J. The relays H, therefore, respond to direct current in the line circuits and the relays J respond to alternating current in the line circuits.

5 Each section is provided with a suitable source of direct current here shown as a battery 9 with its terminals designated by the reference characters B and C.

10 Each section is provided with a transformer designated by the reference character N with a prefix the same as the reference character of the associated signal and having a primary winding 19 and a secondary winding 20 which is connected in series with the associated battery 9.

15 For supplying alternating current to the transformers N, each section is provided with a device, designated by the reference character A with a prefix the same as the reference character of the associated signal, for converting direct current into alternating current. As here shown, each device A is an alternator of the well-known tuned reed type. Referring to the alternator 10A, for example, the reference character 21 designates a reed which is caused to vibrate between terminals 22 and 23 by a control winding 24. In the deenergized condition, reed 21 does not connect with either terminal 22 or terminal 23 but does connect with a terminal 25. When energy is supplied to the alternator 10A, winding 24 will 20 attract reed 21 causing it to connect with terminal 22 and to move away from terminal 25, causing winding 24 to become deenergized. Upon the deenergization of winding 24, the resilience of reed 21 will cause it to move away from terminal 22 and to connect with terminal 23 as well as with terminal 25. The circuit for winding 24 will then be completed so that reed 21 again will go through the cycle of operation just described. Winding 24, therefore, will be repeatedly energized and deenergized as long as energy is supplied to its control circuit. When reed 21 connects with terminal 23, current is then supplied to the right-hand portion of primary winding 19 of transformer 10N; and when reed 21 connects with terminal 22, current is supplied in the opposite direction to the left-hand portion of primary winding 19. Alternating current, therefore, will be induced in the secondary winding 20 of transformer 10N.

40 Energy is supplied to operating winding 24 of alternator 10A whenever the relay 10H is energized in the reverse direction provided the relay 10J is then deenergized, or whenever the relay 10H is energized in the normal direction.

45 The alternators A for each of the other sections are controlled by the associated relays H and J and function to supply alternating current to the associated transformer N in a manner identical to that described for alternator 10A.

50 For controlling the polarity of the direct current supplied to the line circuit for the section next in rear, each section is provided with a slow-releasing relay designated by the reference character HP with a prefix the same as the reference character of the associated signal. Each relay HP is controlled by the associated relays H and J in such a manner that the relay HP is energized whenever the relay J is energized or whenever the relay H is energized in the normal direction provided the relay J is then deenergized.

55 The lamps of the indication units U and L of the signals are controlled by the relays H and J in the following manner: When relay H is deenergized (see signal 14), the red lamp R of the upper unit U of that signal is energized by a cir-

cuit which passes from terminal B through back point of contact 26 of relay 14H and lamp R to terminal C; and the red lamp R of the lower unit L of that signal is energized by a circuit which passes from terminal B through back point of contact 27 of relay 14H and lamp R to terminal C, so that signal 14 displays a red light above a red light to indicate "stop". When relay H is energized in the reverse direction and relay J is deenergized (see signal 13) the yellow lamp Y of the upper unit U of that signal is energized by a circuit which passes from terminal B through front point of contact 28 of relay 13H, normal polar contact 29-30 of relay 13H, and lamp Y to terminal C; and the red lamp R of the lower unit L of that signal is energized by a circuit which passes from terminal B through front point of contact 31 and reverse polar contact 32-33 both of relay 13H, back contact 34 of relay 12J, and lamp R to terminal C, so that signal 13 displays a yellow light above a yellow light to indicate "approach next signal prepared to stop". When relay H is energized in the reverse direction and relay J is energized (see signal 12), the yellow lamp Y of the upper unit U of that signal is energized by a circuit which passes from terminal B through front point of contact 35 of relay 12H, reverse polar contact 29-30 of relay 12H, and lamp Y to terminal C; and lamp Y of the lower unit L of that signal is energized by a circuit which passes over the same path as just described for the yellow lamp of the upper unit including reverse polar contact 29-30 of relay 12H, and thence over front point of contact 33 of relay J and lamp Y to terminal C, so that signal 12 displays a yellow light above a yellow light to indicate "proceed at medium speed". When relay H is energized in the normal direction and relay J is deenergized (see signal 11), the green lamp G of the upper unit U of that signal is energized over a circuit which passes from terminal B through front point of contact 37 of relay 11H, normal polar contact 29-38 of relay 11H, and lamp G to terminal C; and lamp Y of the lower unit L of that signal is energized over the same circuit as just traced for lamp G up to and including normal polar contact 29-38 of relay 11H, and thence over back point of contact 39 of relay 11J to lamp Y and terminal C, so that signal 11 displays a green light above a yellow light to indicate "approach next signal at medium speed". When relay H is energized in the normal direction and relay J also is energized (see signal 10), the green lamp G of the upper unit U of that signal is energized over a circuit which passes from terminal B through front point of contact 40 of relay 10H, normal polar contact 29-38 of relay 10H, and lamp G to terminal C; and the green lamp G of the lower unit L of that signal is energized over the same circuit as just traced for the green lamp of the upper unit, up to and including normal polar contact 29-38 of relay 10H, and thence over front point of contact 41 of relay 10J to lamp G and terminal C, so that signal 10 displays a green light above a green light to indicate "proceed at normal speed".

60 As shown in the drawings, a train K occupies the section immediately to the right of location Z so that the line circuit for the control of relays 14H and 14J is opened. When both relays 14H and 14J are deenergized, relay 14HP is deenergized so that relay 13H is supplied with direct current of reverse polarity over a circuit which passes from terminal B of battery 9 at 65

signal 44, through back point of contact 42 of relay 14HP, front contact 43 of relay 8TR, front contact 44 of relay 7TR, relay 13H, front contact 45 of relay 7TR, front contact 46 of relay 8TR, back point of contact 47 of relay 14HP, and secondary winding 20 of transformer 14N to terminal C.

When relay 13H is energized in the reverse direction and relay 13J is deenergized, relay 13HP remains deenergized but alternator 13A is energized over a circuit which passes from terminal B through back point of contact 48 of relay 13J, front contact 49 and reverse polar contact 50-51 both of relay 13H and winding 24 to terminal C. When relay 13HP is deenergized and alternator 13A is operating, relay 12H is energized in the reverse direction over a circuit which passes from terminal B of battery 9 at signal 13, through back point of contact 52 of relay 13HP, front contact 53 of relay 6TR, front contact 54 of relay 5TR, relay 12H, front contact 55 of relay 5TR, front contact 56 of relay 6TR, back point of contact 57 of relay 13HP, and secondary winding 20 of transformer 13N to terminal C; and primary winding 58 of transformer 12M is energized by alternating current over the same circuit as just described for relay 12H, except including condenser 12F and primary winding 58 of transformer 12M instead of relay 12H. When primary winding 58 is energized, current is induced in secondary winding 59 of transformer 12M so that relay 12J is energized by direct current through asymmetric unit 12Q.

When relay 12H is energized in the reverse direction and relay 12J also is energized, relay 12HP is energized over front point of contact 60 of relay 12J but alternator 12A is deenergized. When relay 12HP is energized and alternator 12A is deenergized, relay 11H is supplied with direct current in the normal direction over a circuit which passes from terminal B of battery 9 at signal 12, through front point of contact 61 of relay 12HP, front contact 62 of relay 4TR, front contact 63 of relay 3TR, relay 11H, front contact 64 of relay 3TR, front contact 65 of relay 4TR, front point of contact 66 of relay 12HP, and secondary winding 20 of transformer 12N to terminal C.

When relay 11H is energized in the normal direction and relay 11J is deenergized, relay 11HP is energized over a circuit which passes from terminal B through back point of contact 67 of relay 11J, front contact 68 of relay 11H, normal polar contact 50-69 of relay 11H, and relay 11HP to terminal C; and alternator 11A is energized over a circuit which passes from terminal B through front contact 70 of relay 11H, normal polar contact 71-72 of relay 11H, and winding 24 of alternator A to terminal C.

When relay 11HP is energized and alternator 11A is energized, relay 10H is energized in the normal direction over a circuit which passes from terminal B of battery 9 at signal 11, through front point of contact 73 of relay 11HP, front contact 74 of relay 2TR, front contact 75 of relay 1TR, relay 10H, front contact 76 of relay 1TR, front contact 77 of relay 2TR, front point of contact 78 of relay 11HP, and secondary winding 20 of transformer 11N to terminal C; and primary winding 58 of transformer 10M is energized by alternating current over the same path as just described for relay 10H, except substituting condenser 10F and primary winding 58 for relay 10H. When primary winding 58 is energized by alternating current, secondary winding

59 of transformer 10M is energized so that relay 10J is energized by direct current through asymmetric unit 10Q.

When relay 10H is energized in the normal direction and relay 10J also is energized, relay 10HP and alternator 10A both are energized over easily traced circuits so that the line circuit for the section immediately in the rear of location V is supplied with alternating current as well as with direct current of normal polarity.

Summing up thus far, each signal is controlled by a polarized direct current line relay and by a neutral direct current line relay. The polarized relay is directly connected to a two-wire line circuit and the neutral relay is connected to the line circuit through an asymmetric unit and a transformer. The line circuit for energizing the polarized and neutral relays associated with the signal for each section is governed by each of the track relays for that section and by the polarized and neutral relays for the signal next in advance.

When both line relays are deenergized, the associated signal will indicate "stop" and the line circuit to the rear will be supplied with direct current only of reverse polarity. When the polarized relay alone is energized in the reverse direction, the associated signal will indicate "prepare to stop at next signal", and the line circuit in the rear will be supplied with direct current of reverse polarity simultaneously with alternating current. When the polarized relay is energized in the reverse direction and the neutral relay also is energized, the associated signal will indicate "proceed at medium speed" and the line circuit to the rear will be supplied with direct current only in the normal direction. When the polarized relay alone is energized in the normal direction, the associated signal will indicate "approach next signal at medium speed" and the line circuit to the rear will be supplied with alternating current simultaneously with direct current of normal polarity. When the polarized relay is energized in the normal direction and the neutral relay also is energized, the associated signal will indicate "proceed at normal speed" and the line circuit to the rear will be supplied with alternating current simultaneously with direct current in the normal direction.

It will be noted that the relays HP have a slow-releasing characteristic. This feature is provided in order to insure that the energization of the line circuits to the rear will not be disturbed during pole-changing periods. For example, when the train K passes out of the section immediately to the right of location Z, relay 12H will be supplied with energy in the normal direction and relay 12J will become deenergized so that signal 12 will indicate "approach next signal at medium speed" instead of its present indication of "proceed at medium speed". When this occurs, the control circuit for relay 12HP will become momentarily opened at front point of contact 60 of relay 12J until such time as front contact 68 and normal polar contact 50-69 of relay 12H can become closed. Relay 12HP, however, will not open the front points of its contacts 61 and 66 so that energization of relay 11H is not disturbed.

Referring next to Figs. 2A and 2B, the system illustrated herein is a three-block, four-indication, signaling system.

Each signal includes an upper unit U comprising a red and a yellow as well as a green lamp, and a lower unit LB comprising a red and a yellow lamp.

Each section is provided with the usual signal

control relays H and J which are connected to the associated line circuit in a manner similar to that described for the apparatus shown in Figs. 1A, 1B, and 1C.

- 5 Each section is provided with the battery 9 and with the transformer N as well as with the alternator A.

The relays HP are controlled in the usual manner by the associated relays H and J.

- 10 The line circuits for the sections next in rear are governed by the relays HP and the alternators A are governed by the relays H and J.

The relays H and J govern the signals in the following manner: When both relays H and J are deenergized (see signal 13), the red lamp R of the upper unit U of that signal is energized over a circuit which passes from terminal B through back point of contact 79 of relay 13H and lamp R to terminal C; and red lamp R of the lower unit LB of that signal is energized over a circuit which passes from terminal B through back contact 80 of relay 13J and lamp R to terminal C, so that signal 13 displays a red light above a red light to indicate "stop". When relay H is energized in the reverse direction and relay J is deenergized (see signal 12), a yellow lamp Y of the upper unit U of that signal is energized over a circuit which passes from terminal B through front point of contact 81 of relay 12H, reverse polar contact 82-83 of relay 12H, and lamp Y to terminal C; and red lamp R of the lower unit LB of that signal is energized over a circuit which passes from terminal B through back contact 84 of relay 12J and lamp R to terminal C, so that signal 12 displays a yellow light above a red light to indicate "approach next signal prepared to stop". When relay H is energized in the reverse direction and relay J also is energized (see signal 11), the yellow lamp Y of the upper unit U of that signal is energized over a circuit which passes from terminal B through front point of contact 85 of relay 11H, reverse polar contact 82-83 of relay 11H, and lamp Y to terminal C; and yellow lamp Y of the lower unit LB of that signal is energized over a circuit which follows the same path as just described for lamp Y of the upper unit, up to and including reverse polar contact 82-83, and thence through front contact 86 of relay 11J and lamp Y to terminal C, so that signal 11 displays a yellow light above a yellow light to indicate "approach next signal at medium speed". When relay H is energized in the normal direction and relay J is deenergized (see signal 10), green lamp G of the upper unit U of that signal is energized over a circuit which passes from terminal B through front point of contact 87 of relay 10H, normal polar contact 82-88 of relay 10H, and lamp G to terminal C; and red lamp R of the lower unit LB of that signal is energized over a circuit which passes from terminal B through back contact 89 of relay 10H and lamp R to terminal C; so that signal 10 displays a green light above a red light to indicate "proceed at normal speed".

As shown in the drawings, the train K occupies the section immediately to the right of location Y so the line circuit for energizing relays 13H and 13J is opened. Consequently, both these relays are deenergized so that relay 13HP also is deenergized. When relay 13HP is deenergized, relay 12H is energized in the reverse direction over a circuit which passes from terminal B of battery 9 at signal 13, through secondary winding 20 of transformer 13N, back point of contact 91 of relay 13HP, front contact 92 of relay 6TR, front contact 93 of relay 5TR, relay 12H, front contact 94 of

relay 5TR, front contact 95 of relay 6TR, and back point of contact 96 of relay 13HP to terminal C of battery 9 at signal 13.

When relay 12H is energized in the reverse direction and relay 12J is deenergized, relay 12HP remains deenergized but alternator 12A is energized over a circuit which passes from terminal B through back point of contact 97 of relay 12J, front contact 98 of relay 12H, reverse polar contact 99-100 of relay 12H, and alternator 12A to terminal C.

When relay 12HP is deenergized and alternator 12A is energized, relay 11H is energized in the reverse direction over a circuit which passes from terminal B of battery 9 at signal 12, through secondary winding 20 of transformer 12N, back point of contact 101 of relay 12HP, front contact 102 of relay 4TR, front contact 103 of relay 3TR, relay 11H, front contact 104 of relay 3TR, front contact 105 of relay 4TR, and back point of contact 106 of relay 12HP to terminal C, and primary winding 58 of transformer 11M is energized simultaneously with alternating current over the same circuit just traced for relay 11H, except that condenser 11F and primary winding 58 should be substituted for relay 11H. When primary winding 58 is energized, current is induced in secondary winding 59 so that relay 11J is energized by direct current through asymmetric unit 11Q.

When relay 11H is energized in the reverse direction and relay 11J also is energized, alternator 11A is deenergized and relay 11HP is energized over a circuit which passes from terminal B through front point of contact 107 of relay 11J and relay 11HP to terminal C.

When relay 11HP is energized, relay 10H is energized in the normal direction over a circuit which passes from terminal B of battery 9 at signal 11, through front point of contact 108 of relay 11HP, front contact 109 of relay 2TR, front contact 110 of relay 1TR, relay 10H, front contact 111 of relay 1TR, front contact 112 of relay 2TR, and front point of contact 113 of relay 11HP to terminal C of the same battery.

When relay 10H is energized in the normal direction and relay 10J is deenergized, alternator 10A is deenergized and relay 10HP is energized by a circuit which passes from terminal B through back point of contact 114 of relay 10J, front contact 115 and normal polar contact 116-117 both of relay 10H, and relay 10HP to terminal C.

When relay 10HP is energized, the line circuit to the rear is supplied over an easily traced circuit with direct current only of normal polarity.

The slow-releasing characteristic of the relays HP prevents tumble-down of signal control circuits to the rear during pole-changing periods in a manner similar to that described for the relays HP shown in Figs. 1A, 1B, and 1C.

To sum up for the signaling system illustrated in Figs. 2A and 2B, each signal is controlled by a polarized direct current relay and by a neutral direct current line relay. The polarized relay is directly connected to a two-wire line circuit and the neutral relay is connected to the line circuit through an asymmetric unit and a transformer. The line circuit is governed by each of the associated track relays and by the polarized and neutral relays for the signal next in advance.

When both line relays are deenergized, the associated signal will indicate "stop" and the line circuit to the rear will be supplied with direct current only of reverse polarity. When the polarized relay alone is energized in the reverse direction, the associated signal will indicate "ap-

proach next signal prepared to stop" and the line circuit to the rear will be supplied with alternating current energy simultaneously with direct current of reverse polarity. When the polarized relay is energized in the reverse direction and the neutral relay also is energized, the associated signal will indicate "approach next signal at medium speed" and the line circuit to the rear will be supplied with direct current only of normal polarity. When the polarized relay only is energized in the normal direction, the associated signal will indicate "proceed at normal speed", and the line circuit to the rear will be supplied with direct current only of normal polarity.

Referring now to Fig. 3, the reference characters BX and CX designate the terminals of a source of alternating current such, for example, as any convenient commercial source, which may be substituted at each signal for the alternator A.

As here shown, this source of alternating current is utilized for charging the battery 9 through a rectifier QA and is also utilized to supply alternating current to the primary winding 118 of transformer NA, the secondary winding 119 of

which is connected in series with the battery 9 and the line circuit to the rear when relay HP is deenergized. The circuit for supplying energy to primary winding 118 of transformer NA may be traced from terminal BX through back contact 97 of relay J, front contact 98 of relay H, and reverse polar contact 99-100 of relay H, and primary winding 118 to terminal CX. That is, alternating current energy is supplied simultaneously with direct current energy to the line circuit for the section next in rear in a manner similar to that described for the apparatus shown at signal 12 in Figs. 2A and 2B. In other words, when relay H is energized in the reverse direction and relay J is deenergized so that the associated signal will indicate "approach next signal prepared to stop", the line circuit to the rear will be supplied with alternating current simultaneously with direct current of reverse polarity so that the signal controlled by that line circuit will indicate "approach next signal at medium speed".

The circuits for the control of the signal lamps and the relay HP are identical in all respects to those shown and described for the apparatus shown in Figs. 2A and 2B.

Referring next to Fig. 4, the circuits for the control of the signal lamps and the relay HP, by the relays H and J, are identical in all respects to those shown in Figs. 2A and 2B.

As here shown, the terminals BX and CX of the commercial source of alternating current are connected to the rectifier QA for charging the battery 9 and also are connected to an alternating current power-off relay PO.

The relay PO, when energized, is effective for connecting the primary winding 19 of transformer N to the terminals BX and CX and, when deenergized, is effective for connecting the primary winding 19 to the alternator A. That is, when the commercial source of alternating current is present, the alternating current energy required by the line circuit to the rear is supplied from that source and, when the commercial source is absent, the alternating current energy required by the line circuit to the rear is supplied by the alternator A. It is, of course, apparent that the secondary winding 20 of transformer N is connected in series with the line circuit to the rear when the relay HP is deenergized in a manner identical to that described for the transformer N shown in Figs. 2A and 2B.

The circuit for supplying alternating current energy to primary winding 19 of transformer N, when relay PO is energized, may be traced from terminal BX through back contact 120 of relay J, front contact 121 and reverse polar contact 122-123 both of relay H, front point of contact 124 of relay PO, primary winding 19, and front point of contact 125 of relay PO to terminal CX. The circuit for the control of alternator A may be traced from terminal B through back contact 97 of relay J, front contact 98 and reverse polar contact 99-100 both of relay H, back contact 126 of relay PO, and winding 24 of alternator A to terminal C. It is obvious that, when alternator A is operating and back points of contacts 124 and 125 of relay PO are closed, primary winding 19 of transformer N will be alternately energized in one direction and then in the other so that alternating current will be induced in secondary winding 20.

Referring next to Fig. 5, the signal lamps and the relay HP are controlled by the relays H and J in a manner identical to that shown and described for the apparatus shown in Figs. 2A and 2B.

As here shown, the terminals BX and CX of the commercial source of alternating current are connected to the rectifier QA for charging the battery 9 and are connected to the power-off relay PO.

When relay PO is energized so that the front points of its contacts 124 and 125 are closed, secondary winding 119 of transformer NA supplies the alternating current required by the line to the rear; and when relay PO is deenergized so that the back points of its contacts 124 and 125 are closed, secondary winding 20 of transformer N supplies the alternating current required by the line circuit to the rear. That is, when relay HP is deenergized, either secondary winding 119 of transformer NA or secondary winding 20 of transformer N is connected in series with the line circuit in the rear depending upon whether relay PO is energized or deenergized, respectively. Primary winding 118 of transformer NA may be energized over a circuit which includes back contact 120 of relay J and front contact 121 of relay H as well as reverse polar contact 122-123 of relay H. The alternator A may be energized to supply alternating current to primary winding 19 of transformer N over a circuit which includes back contact 97 of relay J, and front contact 98 and reverse polar contact 99-100 both of relay H as well as back contact 126 of relay PO.

In other words, when relay H is energized in the reverse direction and relay J is deenergized so that relay HP is deenergized, the line circuit for the section next in rear will be supplied with direct current of reverse polarity from battery 9 and with alternating current from the commercial source, or from the alternator A in the event of failure of the commercial source.

Although the modifications shown in Figs. 3, 4, and 5 are shown applied to one signal only, it is understood that the circuits and apparatus at any or all signals shown in Figs. 2A and 2B may be modified in a similar manner if desired. Furthermore, the signals shown in Figs. 1A, 1B, and 1C, also, may be controlled by alternating current energy from a commercial source or from an alternator in a manner similar to that shown and described in Figs. 3, 4, and 5, if desired.

Referring now to Fig. 6, I have herein shown one signal and associated apparatus which, when connected in a system, will function to provide

three-block, four-indication, signaling in a manner similar to that described for the apparatus illustrated in Figs. 2A and 2B. The principal difference is in the type of signal utilized and in the manner in which the signal is controlled by the relays H and J.

As here shown, the signal includes an upper indication unit UA and a lower indication unit LA. The unit UA is the well-known semaphore arm capable of assuming a horizontal or "stop" position, a 45° or "caution" position and a vertical or "proceed" position. The unit LA comprises a yellow lamp Y.

Associated with the semaphore arm UA is a lamp E which, when lighted, provides the usual and well-known supplementary color light indications corresponding to the positions of the semaphore arm.

For controlling the lamp E and the lamp Y, a normally energized approach lighting relay ER is connected in series with the line circuit for the section next in rear. That is, when such rear section becomes occupied so that relay ER becomes released to close its back contact 127, lamp E will be then energized and lamp Y will be energized provided its control circuit, to be traced later, is then closed.

It will be noted that a resistor 134 is connected around the relay ER. This resistor is provided to bypass the greater portion of the alternating current supplied to the line circuit in the rear since the impedance of the relay ER usually will be of such value as to retard appreciably the flow of alternating current. If desired, a condenser may be utilized for this purpose instead of a resistor.

Operably connected to semaphore arm UA are contacts 128 and 129 as well as contact 130. Contact 128 is in engagement with contact 131 at all times except when the semaphore arm is in the proceed position. Contact 129 is in engagement with contact 132 when the semaphore arm is in its caution position or in its proceed position or at any point between these two positions. Contact 130 is in engagement with contact 133 when the semaphore arm is in the 55° position (above horizontal) or is in the proceed position or at any point between these positions.

The signal is provided with an operating battery, the terminals of which are designated by the reference characters BO and CO, and with a line battery 9L, the terminals of which are designated by the reference characters BL and CL.

The usual alternator A and transformer N are provided for supplying alternating current, and the usual repeating relay HP is provided for controlling the currents supplied to the line circuit in the rear.

The relay H is connected to its line circuit by signal contact 128-131 so that when the semaphore arm is in the proceed position the relay H becomes deenergized. When the relay H is deenergized, the semaphore arm receives its energy directly from the line circuit over back contacts of the relay H. This feature provides for unusually low current consumption since the only current necessary, when the signal is in the normal proceed position, is the current required to hold the semaphore arm in that position and the current required to energize the relay HP. The holding current required by the semaphore arm and by the relay HP is relatively small so that the cost of current for my system is unusually low and results in an appreciable saving, particu-

larly when the current is supplied by primary batteries.

The relay J is connected to secondary winding 59 of transformer M through the usual asymmetric unit Q, and the primary 58 of transformer M is connected to the line circuit through a resistor D. The resistor D performs the same function as the condenser F in the preceding figures, that is, it limits the flow of direct current in the primary winding 58. If the value of the 10 resistance of primary winding 58 is sufficiently high, the resistors D and condensers F may be dispensed with as the transformer M will prevent the energization of relay J by direct current in the line circuit.

When the forward section is occupied so that the line circuit for that section is opened, the semaphore arm UA will become deenergized and will assume its horizontal position to indicate "stop".

When the semaphore arm is in its horizontal position, relay HP will become deenergized and alternator A will remain deenergized so that the line circuit to the rear will be supplied, over back points of contacts 146 and 147 of relay HP, with direct current only of reverse polarity from the line battery 9L.

When relay H alone is energized in the reverse direction, a caution circuit for semaphore arm UA will be closed over a path which passes from terminal BO through front point of contact 135 of relay H, semaphore arm UA, and front point of contact 136 of relay H to terminal CO. The signal will then display its semaphore arm UA in the caution position to indicate "approach next signal prepared to stop".

With the signal displaying this indication and with relay H only energized in the reverse direction, relay HP will remain deenergized but alternator A will become energized over a circuit which passes from terminal BO through signal contact 129-132, back point of contact 137 of relay J, front contact 138 and reverse polar contact 139-140 both of relay H, and operating winding 24 of alternator A to terminal CO.

When relay HP is deenergized and alternator A is operating to supply alternating current to transformer N, the line circuit to the rear will be supplied with alternating current simultaneously with direct current of reverse polarity over back points of contacts 146 and 147 of relay HP.

When relay H is energized in the reverse direction and relay J also is energized, the caution circuit for semaphore arm UA will remain closed and a circuit for lamp Y, which includes front point of contact 135 and reverse polar contact 141-142, both of relay H, as well as front contact 143 of relay J, will be established so that the signal will be in condition, when relay ER becomes deenergized, to display a yellow light below the semaphore arm in the caution position to indicate "approach next signal at medium speed".

With the signal in this condition and with relay J energized, the alternator A will become deenergized because of the picking up of contact 137 of relay J, and the relay HP will become energized so that the line circuit to the rear will be supplied with direct current only in the normal direction over front points of contacts 146 and 147 of relay HP. The circuit for energizing relay HP includes terminal BO, signal contact 129-132, front contact 137 of relay J, and winding of relay HP.

When relay H is energized in the normal direction and relay J is deenergized, the caution circuit for the semaphore arm will remain closed and a proceed circuit for the semaphore arm will be closed over a path which passes from terminal BO through front point of contact 135 of relay H, normal polar contact 141-144 of relay H, semaphore arm UA, and front point of contact 136 of relay H to terminal CO, so that the semaphore arm UA will assume its vertical position to indicate "proceed at normal speed".

When the semaphore arm UA attains its vertical position, contact 128-131 will become opened so that relay H will become deenergized. When relay H is deenergized, the caution and proceed circuits for semaphore arm UA will be connected directly to the line circuit over back points of contacts 135 and 136 of relay H so that the semaphore arm will be maintained in the proceed position.

The relay HP will be maintained in its energized condition when the relay H is energized in the normal direction and the relay J is deenergized, provided signal contact 129-132 is then closed, by a circuit which passes from terminal BO through signal contact 129-132, back point of contact 137 of relay J, front contact 138 and normal polar contact 139-145 both of relay H, and relay HP to terminal CO.

When the semaphore arm is in the vertical position, a second circuit for relay HP, including signal contact 130-133, will be closed so that this relay will be maintained in the energized condition to supply direct current only in the normal direction to the line circuit in rear over front points of contacts 146 and 147 of relay HP.

The relay HP is provided with a slow-release characteristic so that, during pole-changing periods, the energization of the line circuit to the rear is not disturbed.

Summing up for the signal and associated apparatus shown in Fig. 6, it will be seen that the line circuit for the section first in rear of an occupied section is supplied with direct current energy only of reverse polarity to cause the signal for such rear section to indicate "prepare to stop at next signal"; that the line circuit for the section second in rear of an occupied section will be supplied with alternating current simultaneously with direct current of reverse polarity to cause the signal controlled by such second section in rear to indicate "approach next signal at medium speed"; and that the line circuit for the section third in rear of an occupied section and each successive section will be supplied with direct current only of normal polarity to cause the signals controlled by such rear line circuits to indicate "proceed at normal speed".

Referring next to Fig. 7, the signal and associated apparatus shown therein will function in a manner similar to that described for the apparatus shown in Fig. 6, the principal difference being in the manner in which the currents for the line circuit for the section next in rear are controlled.

In addition to signal contact 128-131, the semaphore arm UA operates pole-changing contacts 149, 150, 151, and 152. Contacts 149 and 150 are in engagement with contacts 153 and 154, respectively, when the semaphore arm is at any point between the 43° position (above horizontal) and the vertical position, and are in engagement with contacts 155 and 156, respectively, when the semaphore arm is at any point below 75 the 43° position. Contacts 151 and 152 are in

engagement with contacts 157 and 158, respectively, when the semaphore arm is at any point between the 60° position (above horizontal) and the vertical position, and are in engagement with contacts 159 and 160, respectively, when the 5 semaphore arm is at any point below the 60° position.

The signal lamps E and Y are controlled by back contact 127 of approach lighting relay ER which is connected in series with the line circuit 10 for the section next in rear.

For supplying the alternating current required for the rear line circuit, the transformer NA is provided having its primary winding 118 connected to terminals BX and CX of any convenient 15 source of alternating current and having its secondary winding 119 connected in series with the line circuit to the rear when that line circuit is to be supplied with alternating current.

When the line circuit is opened, the semaphore 20 arm UA will assume its horizontal position to indicate "stop".

When the relay H only is energized in the reverse direction, semaphore arm UA will be energized over a caution circuit which passes from 25 terminal BO through front point of contact 161 of relay H, semaphore arm UA, and front point of contact 162 of relay H to terminal CO so that the signal will display the semaphore arm in the caution position to indicate "approach next signal prepared to stop".

When relay H is energized in the reverse direction and relay J also is energized, the caution circuit for semaphore arm UA will remain closed and a circuit including front contact 163 of relay 35 J and front contact 164 of relay H will be established for lamp Y so that, when relay ER becomes deenergized, the signal will display a yellow light below the semaphore arm in the caution position to indicate "approach next signal at 40 medium speed".

When the relay H only is energized in the normal direction, the caution circuit will remain closed and a proceed circuit for the semaphore arm will be closed over a path which passes from 45 terminal BO through front point of contact 161 of relay H, normal polar contact 165-166 of relay H, semaphore arm UA, and front point of contact 162 of relay H to terminal CO, so that the signal will display the semaphore arm in the proceed position to indicate "proceed at normal speed".

When the semaphore arm is in the proceed position, signal contact 128-131 will become opened so that relay H will become deenergized to connect, directly to the line circuit over back points of contacts 161 and 162, the caution and proceed circuits for semaphore arm UA.

When the semaphore arm is in the stop condition, the line circuit to the rear will be supplied 60 with direct current only of reverse polarity over a circuit which includes pole-changing contacts 150-156 and 149-155.

When the semaphore arm is in the caution position and relay J is deenergized, the line circuit to the rear will be supplied with alternating current simultaneously with direct current of reverse polarity over a circuit which includes back points of contacts 167 and 168 of relay J, and signal contacts 151-159 and 152-160 as well as 70 signal contacts 149-153 and 150-154.

When the semaphore arm is in the caution position and relay J is energized, the line circuit to the rear will be supplied with direct current only of normal polarity over a circuit which includes 75

front points of contacts 167 and 168 of relay J, and signal contacts 151—159 and 152—160 as well as signal contacts 149—153 and 150—154.

When the semaphore arm is in the proceed position, the line circuit to the rear is supplied with direct current only of normal polarity over a circuit which includes signal contacts 151—157 and 152—158 as well as signal contacts 149—153 and 150—154.

10 It will be noted that with this arrangement for controlling the supply of current to the line circuit in the rear, the necessity for the pole-changing relay HP is dispensed with.

Referring next to Fig. 8, the signal and associated apparatus is substantially the same as shown in Fig. 6 except in the manner in which the direct current and alternating current is supplied to the line circuit in the rear.

In addition to signal contact 128—131, the semaphore arm UA is provided with signal contacts 170, 171, 172, and 173. Contact 170 is in engagement with contact 174 when the semaphore arm is in the 43° position (above horizontal) or in the 89° position or at any point between these two positions. Similarly, contact 171 is in engagement with contact 175 when the semaphore arm is at any point between the 43° position and the 89° position. Contacts 172 and 173 are in engagement with contacts 176 and 177, respectively, when the semaphore arm is in the 55° position or in the proceed position or at any point between these two positions, and are in engagement with contacts 178 and 179, respectively, when the semaphore arm is at any point below the 55° position.

When the line circuit is opened, semaphore arm UA will assume the horizontal position to indicate "stop".

When the relay H only is energized in the reverse direction, semaphore arm UA will be energized over a caution circuit which passes from terminal BO through front point of contact 180 of relay H, semaphore arm UA, and front point of contact 181 of relay H to terminal CO, so that 45 the signal will display the semaphore arm in the caution position.

When the relay H is energized in the reverse direction and the relay J also is energized, the caution circuit for semaphore arm UA will remain closed and relay HP will be energized, providing semaphore arm UA is in the caution position, over a circuit which passes from terminal BO over front point of contact 180 of relay H, reverse polar contact 182—183 of relay H, front 50 point of contact 184 of relay J, signal contact 170—174, front contact 185 of relay H, and relay HP to terminal CO.

When relay J is energized and relay HP also is energized, a circuit, including front point of 55 contact 186 of relay HP and front contact 187 of relay J, will be established for lamp Y so that when relay ER is released, the signal will display a yellow lamp below the semaphore arm in the caution position.

60 When the relay H only is energized in the normal direction, the caution circuit for the semaphore arm will remain closed and a proceed circuit will be closed over a path which passes from terminal BO through front point of contact 180 of relay H, normal polar contact 182—188, semaphore arm UA, and front point of contact 181 of relay H to terminal CO so that the semaphore arm will assume the proceed position.

When the semaphore arm is in the proceed 65 position, signal contact 128—131 will become

opened so that relay H will become deenergized to connect semaphore arm UA to the line circuit over back contacts 180 and 181 of relay H.

When the semaphore arm is in the stop position, relay HP will become deenergized because of release of contact 185 of relay H so that the line circuit to the rear will be supplied with direct current only of reverse polarity from line battery 9L, over a circuit which includes signal contacts 172—178 and 173—179 as well as back 10 points of contacts 189 and 190 of relay HP and relay ER in multiple with resistor 134.

When the semaphore arm is in the caution position and relay J is deenergized, relay HP will remain deenergized and the alternator A will be 15 energized over a circuit which passes from terminal BO through back point of contact 186 of relay HP, signal contact 171—175, and winding 24 of alternator A to terminal CO, so that the line circuit to the rear will be supplied with 20 alternating current simultaneously with direct current of reverse polarity over a circuit which includes relay ER and resistor 134 in multiple, and signal contacts 172—178 and 173—179, as well as back points of contacts 189 and 190 of 25 relay HP.

When the semaphore arm is in the caution position and the relay J is energized, relay HP will be energized, provided relay H is then energized in the reverse direction, over the pickup circuit for relay HP already traced so that alternator A will become deenergized and the line circuit to the rear will be supplied with direct current only in the normal direction over a circuit which includes relay ER and resistor 134 in multiple as well as front points of contacts 189 and 190 of relay HP.

When the semaphore arm is in the proceed position, relays H and HP become deenergized and the line circuit to the rear is supplied with direct current only of normal polarity over a circuit which includes relay ER and resistor 134 in multiple and signal contacts 172—176 and 173—177.

Referring now to Fig. 9, I have herein shown 45 how one alternator A may be controlled for supplying alternating current for the signal systems for each of two parallel tracks.

As here shown, each track is provided with a signal and associated apparatus which, except 50 for the manner in which alternating current is supplied to the line circuit in the rear, is identical in all respects to the signal and associated apparatus shown in Fig. 8.

The signal for the lower track is provided with 55 signal contact 191—192 which is closed at the same time as signal contact 171—175, that is, when the semaphore arm UA is in the 43° position (above horizontal) or in the 89° position or at any point between these two positions.

Similarly, the signal for the upper track is provided with contacts 193—194 and 195—196 each of which is closed when the semaphore arm for that signal is in the 43° or 89° positions or at any point between these positions.

The alternator A is provided with two easily 60 traced energizing circuits one of which includes signal contact 191—192 and the other of which includes contact 195—196, so that the alternator will operate when either semaphore arm is in the 70 caution position.

When the alternator is operating, alternating current will be supplied to primary winding 19 of transformer N, the secondary winding 20 of which is connected, by signal contact 171—175 of the 75

signal for the lower track and back contact 197 of relay HP for that signal, to the primary winding 118 of transformer NA for that signal; and by signal contact 193—194 of the signal for the upper track and back contact 198 of relay HP for that signal, to the primary winding 118 of transformer NA for that signal.

Since the secondary windings 119 of the transformers NA are connected in the usual manner 10 with the line circuits in rear of their respective signals, it will be obvious how alternating current is supplied to such line circuits from the single alternator A.

Although, in Fig. 9, I have shown only one signal 15 and associated apparatus for each track, it will be understood that each signal, when connected in a system, will function to provide four indication, three-block signaling for the respective tracks.

Although I have herein shown and described 20 only a few forms of apparatus embodying my invention, it is understood that various changes and modifications may be made therein within the scope of the appended claims without departing 25 from the spirit and scope of my invention.

Having thus described my invention, what I claim is:

1. A railway signal system comprising a plurality of successive sections of railway track each 30 having a pair of conductors governed by traffic conditions in said section, means effective when one section is occupied to supply the conductors for the section first in rear of such occupied section with current of one character, means then effective to supply the conductors for the section second in rear of such occupied section with current of another character simultaneously with current of said one character, means then effective to supply the conductors for the section third in rear of such occupied section with current of still a different character, and signaling means for each section governed by the associated conductors and selectively responsive to the character and number of the currents with which such conductors are supplied.

2. A railway signal system comprising a plurality of successive sections of railway track each having a pair of conductors governed by traffic 40 conditions in said section, means effective when one section is occupied to supply the conductors for the section first in rear of such occupied section with current of one character, means then effective to supply the conductors for the section second in rear of such occupied section with current of another character simultaneously with current of said one character, means then effective to supply the conductors for the section third in rear of such occupied section with current of still a different character, means then effective to supply the conductors for the fourth section in rear of such occupied section with current of said other character simultaneously with current of said different character, and signaling means for each section governed by the associated conductors and selectively responsive to the character and number of the currents with which such conductors are supplied.

3. A railway signal system comprising; a first, a second, a third, and a fourth track section 50 over which traffic normally progresses in the order named, a pair of conductors for each section governed by traffic conditions in such section, a polarized direct current relay for each section receiving energy from the associated conductors, 55 a neutral direct current relay for each section

receiving energy from the associated conductors through an asymmetric unit, a signal for each section governed by the associated polarized and neutral relays, means effective when the fourth section is occupied to supply the conductors for the third section with direct current only of reverse polarity, means then effective to supply the conductors for the second section with alternating current simultaneously with direct current of reverse polarity, and means then effective 10 to supply the conductors for the first section with direct current only of normal polarity.

4. A railway signal system comprising a first, a second, a third, a fourth, and a fifth track section over which traffic normally progresses in the order named, a pair of conductors for each section governed by traffic conditions in said section, a polarized direct current relay for each section connected to the associated conductors, a neutral direct current relay for each section receiving 20 energy from the associated conductors through an asymmetric unit, a signal for each section governed jointly by the associated polarized and neutral relays, means effective when the fifth section is occupied to supply the conductors for 25 the fourth section with direct current only of reverse polarity, means then effective to supply the conductors for the third section with alternating current simultaneously with direct current of reverse polarity, means then effective to supply 30 the conductors for the second section with direct current only of normal polarity, and means then effective to supply the conductors for the first section with alternating current simultaneously with direct current of normal polarity. 35

5. In combination, a plurality of successive sections of railway track, a pair of conductors for each section governed by traffic conditions in said section, a direct current polarized relay for each section receiving energy from the associated conductors, a neutral direct current relay for each section, means including a transformer and a rectifier as well as a condenser for connecting each neutral relay to the associated conductors, means for each section for supplying direct current only of reverse polarity to the conductors for the section next in rear when both the polarized relay and the neutral relay are deenergized, means for each section for supplying alternating current simultaneously with direct current of reverse polarity to such conductors in rear when the polarized relay is energized reverse and the neutral relay is deenergized, means for each section for supplying direct current only of normal polarity to such conductors next in rear when the polarized relay is energized reverse and the neutral relay is energized, means for each section for supplying alternating current simultaneously with direct current of normal polarity to such conductors next in rear when said polarized relay is energized normal and said neutral relay is deenergized, means for each section for supplying alternating current simultaneously with direct current of normal polarity to such conductors next in rear when said polarized relay is energized normal and said neutral relay is energized, and a signal for each section governed by the associated polarized and neutral relays. 55

6. In combination, a plurality of successive sections of railway track, a pair of conductors 70 for each section governed by traffic conditions in said section, a direct current polarized relay for each section receiving energy from the associated conductors, a neutral direct current relay also receiving energy from the associated conductors 75

- through an asymmetric unit, means for each section for supplying direct current only of reverse polarity to the conductors for the section next in rear when both the polarized and the neutral relays are deenergized, means for each section for supplying alternating current simultaneously with direct current of reverse polarity to such conductors next in rear when the polarized relay is energized reverse and the neutral relay is deenergized, means for each section for supplying direct current only of normal polarity to such conductors next in rear when the neutral relay is energized, means for each section for supplying direct current only of normal polarity to such conductors next in rear when the polarized relay is energized normal and the neutral relay is deenergized, and a signal for each section governed jointly by the associated polarized and neutral relays.
7. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, and means for each section for also supplying such conductors for the section next in rear with alternating current effective when said slow-acting relay is deenergized provided the associated polarized relay is then energized in the reverse direction and the associated neutral relay is then deenergized.
8. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section, a circuit for said slow-acting relay including a front contact of the associated neutral relay, another circuit for said slow-acting relay including a back contact of said neutral relay and a front contact of the associated polarized relay as well as a normal polar contact of said polarized relay, means for each section for supplying the conductors for the section next in rear with direct current of normal polarity or of reverse polarity according as said slow-acting relay is energized or deenergized respectively, and means for each section for also supplying such conductors for the section next in rear with alternating current effective when the associated slow-acting relay is deenergized provided the associated polarized relay is then energized in the reverse direction and the associated neutral relay is then deenergized.
9. In combination, a railway track divided into sections, a pair of conductors for each section

governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, and means for each section for also supplying such conductors for the section next in rear with alternating current effective when the associated polarized relay is energized in the normal direction or when the associated neutral relay is deenergized provided the polarized relay is then energized in the reverse direction.

10. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, and means for each section including a tuned reed alternator for also supplying such conductors for the section next in rear with alternating current effective when the associated polarized relay is energized in the normal direction or when the associated neutral relay is deenergized provided the polarized relay is then energized in the reverse direction.

11. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, and means for each section including a tuned reed alternator for also supplying such conductors for the section next in rear with alternating current effective when the associated

slow-acting relay is deenergized provided the associated polarized relay is then energized in the reverse direction and the associated neutral relay is then deenergized.

5 12. In combination, a railway track divided into sections, a pair of conductors for each section governed by traffic conditions in said section, a direct current polarized relay for each section receiving energy from the associated conductors, 10 a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the 15 conductors for the section next in rear with direct current of normal polarity or with direct current of reverse polarity according as the associated slow-acting relay is energized or deenergized respectively, a transformer for each section having a primary winding and a secondary winding, means for each section including a back contact of the associated slow-acting relay for connecting the secondary winding of the associated transformer in series with such conductors for the section next in rear, and means for each section for supplying the primary winding of the associated transformer with alternating current effective when the associated polarized relay is energized in the reverse direction provided the 20 associated neutral relay is then deenergized.

35 13. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, a transformer for each section having a primary winding and a secondary winding, means for each section including a back contact of the associated slow-acting relay for connecting the secondary winding of the associated transformer in series with such conductors for the section next in rear, an alternator for each section having its output terminals connected to the primary winding of the associated transformer, and a circuit for energizing each alternator including a back contact of the associated neutral relay and a front contact as well as a reverse polar contact of the associated polarized relay.

40 14. In combination, a railway track divided into sections, a pair of conductors for each section governed by traffic conditions in said section, a direct current polarized relay for each section receiving energy from the associated conductors, a direct current neutral relay for each section receiving energy from the associated conductors,

45 through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, an alternator for each section, a transformer for each section having its primary connected to the output terminals of the associated alternator and its secondary winding connected in series with one of the conductors for the section next in rear, a circuit for energizing each alternator including a back contact of the associated neutral relay and a front contact as well as a reverse polar contact of the associated polarized relay and another circuit for energizing each alternator including a front contact and a normal polar contact of the associated polarized relay.

50 15. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction, means for each section for supplying the conductors for the section next in rear with direct current of normal polarity or with direct current of reverse polarity according as the associated slow-acting relay is energized or deenergized respectively, a transformer for each section having a primary winding and a secondary winding, a first source of alternating current for each section, a second source of alternating current for each section, a transfer relay for each section connected to the first associated source of alternating current, means for each section including a back contact of the associated slow-acting relay for connecting the secondary winding of the associated transformer to the conductors for the section next in rear, and means for each section for connecting the primary winding of the associated transformer to said first associated source of alternating current or to said second associated source of alternating current according as said transfer relay is energized or deenergized respectively.

55 16. In combination, a railway track divided into sections, a pair of conductors for each section governed by traffic conditions in said section, a direct current polarized relay for each section receiving energy from the associated conductors, a direct current neutral relay for each section receiving energy from the associated conductors through an asymmetric unit, a signal for each section governed by the associated neutral and polarized relays, a slow-acting relay for each section which is energized when the associated neutral relay is energized or when the associated neutral relay is deenergized and the associated polarized relay is energized in the normal direction.

tion, means for each section for supplying the conductors for the section next in rear with direct current of normal polarity or with direct current of reverse polarity according as the associated slow-acting relay is energized or deenergized respectively, a transformer for each section having a primary winding and a secondary winding, a first source of alternating current for each section, a second source of alternating current for each section, means for each section for connecting the secondary winding of the associated transformer in series with one of the conductors for the section next in rear when the associated slow-acting relay is deenergized, means for each section for connecting the primary winding of the associated transformer to the first associated source of alternating current, and means for each section for connecting the primary winding of the associated transformer to the second associated source of alternating current when said first source is absent.

17. A section of railway track, a pair of conductors governed by traffic conditions in said section, a direct current relay connected to said conductors, another direct current relay connected to said conductors through an asymmetric unit, means governed by traffic conditions in advance of said section for supplying said conductors with direct current only or with direct current simultaneously with alternating current, a signal for said section governed by said two relays in such a manner that the signal will display its least restrictive aspect when said first relay only is energized, and means effective when said signal is displaying its least restrictive aspect to connect said signal to said conductors and to disconnect said first relay from said conductors.

18. A section of railway track, a pair of conductors governed by traffic conditions in said section, a direct current relay connected to said conductors, another direct current relay connected to said conductors through an asymmetric unit, means governed by traffic conditions in advance of said section for supplying said conductors with direct current only or with direct current simultaneously with alternating current, a signal for said section governed by said two relays in such a manner that the signal will display its least restrictive aspect when said first relay only is energized, means including a contact operably governed by said signal effective to disconnect said first relay from said conductors when the signal is displaying its least restrictive aspect, and means including a back contact of said first relay for then connecting said signal to said conductors.

19. In combination, a railway track divided into sections, each section having a pair of conductors governed by traffic conditions in such section, a signal for each section governed by the associated conductors, means for each section governed by the associated signal for supplying the conductors for the section next in rear with alternating current simultaneously with direct current or with direct current only, each of said last mentioned means including an alternator controlled by a contact operably governed by the associated signal.

20. In combination, a railway track divided into sections, each section having a pair of conductors governed by traffic conditions in such section, means including an alternator and governed in accordance with traffic conditions in advance of each section for supplying the associated conductors with alternating current simul-

taneously with direct current or for supplying such conductors with direct current only, a signal for each section governed by the associated conductors, another pair of conductors for a parallel track for governing a signal for that track, and means including said alternator for at times supplying alternating current to said other conductors.

21. In combination, a forward and a rear section of railway track, a pair of conductors for the forward section, a first direct current relay controlled by said conductors, a second direct current relay controlled by said conductors through an asymmetric unit, means controlled by traffic conditions in advance of said forward section for supplying said conductors with direct current only or with alternating current simultaneously with direct current, a signal for the forward section governed by said first and second relays, an alternator for the forward section for supplying alternating current to a pair of conductors for the rear section, means including a contact operably governed by said signal for energizing said alternator when that signal is displaying a particular indication, another signal for a parallel track, means including a contact operably governed by said other signal for also energizing said alternator, and another pair of conductors for said parallel track also receiving alternating current from said alternator.

22. In combination, a section of railway track having a pair of conductors governed by traffic conditions in said section, means governed by traffic conditions in advance of said section for supplying said conductors with direct current only of normal polarity or with direct current only of reverse polarity or with alternating current simultaneously with direct current of normal polarity or with alternating current of reverse polarity, a direct current polarized relay connected to said conductors, a direct current neutral relay receiving energy from said conductors through an asymmetric unit, a signal for said section including a first indication unit and a second indication unit each comprising a red and a yellow as well as a green lamp, a circuit for the red lamp of the first unit including a back contact of the polarized relay, a circuit for the red lamp of the second unit including a back contact of the polarized relay, another circuit for the red lamp of the second unit including a front contact and a reverse polar contact of the polarized relay as well as a back contact of the neutral relay, a circuit for the yellow lamp of the first unit including a front contact and a reverse polar contact of the polarized relay, a circuit for the yellow lamp of the second unit including a front contact and a reverse polar contact of the polarized relay, another circuit for the yellow lamp of the second unit including a front contact and a normal polar contact of the polarized relay as well as a back contact of the neutral relay, a circuit for the green lamp of the first unit including a front contact and a normal polar contact of the polarized relay, and a circuit for the green lamp of the second unit including a front contact and a normal polar contact of the polarized relay as well as a front contact of the neutral relay.

23. In combination, a section of railway track having a pair of conductors governed by traffic conditions in said section, means governed by traffic conditions in advance of said section for supplying said conductors with direct current only

of normal polarity or with direct current only of reverse polarity or with alternating current simultaneously with direct current of reverse polarity, a direct current polarized relay connected to said conductors, a direct current neutral relay receiving energy from said conductors through an asymmetric unit, a signal for said section including a first unit comprising a red lamp and a yellow lamp as well as a green lamp and a second unit comprising a yellow lamp and a red lamp, a circuit for the red lamp of the first unit including a back contact of the polarized relay, a circuit for the red lamp of the second unit including a back contact of the neutral relay, a circuit for the yellow lamp of the first unit including a front contact and a reverse polar contact of the polarized relay, a circuit for the yellow lamp of the second unit including a front contact and a reverse polar contact of the polarized relay as well as a front contact of the neutral relay, and a circuit for the green lamp of the first unit including a front contact and a normal polar contact of the polarized relay.

24. In combination, a section of railway track having a pair of conductors governed by traffic conditions in said section, means governed by traffic conditions in advance of said section for supplying said conductors with direct current only of normal polarity or with direct current only of reverse polarity or with alternating current simultaneously with direct current of reverse polarity, a direct current polarized relay receiving energy from said conductors, a direct current neutral relay receiving energy from said conductors, a signal for said section including a first unit comprising a mechanism and a second unit comprising a lamp, a circuit for said mechanism including a front contact of said polarized relay, another circuit for said mechanism including said front contact as well as a normal polar contact of said polarized relay, and a circuit for said lamp including a front contact and a reverse polar contact of said polarized relay as well as a front contact of said neutral relay.

25. In a signal system for railroads, in combination, a stretch of track divided into track sections, a signal located at the entrance of each track section having two indicators, an operating mechanism for each indicator, one pair of conductors only for interconnecting adjacent signals, means for controlling each signal by applying current of different characters to said one pair of conductors in accordance with traffic conditions ahead, and means for automatically cutting in an auxiliary current supply of one character in the event of a failure of the current supply of said one character. 5

26. In a signal system for railroads, in combination, a stretch of track divided into track sections, a signal located at the entrance of each track section having two indicators, an operating mechanism for each indicator, one pair of conductors only for interconnecting adjacent signals, means for controlling said signals by applying alternating current and direct current to said one pair of conductors in accordance with traffic conditions ahead and automatic means for manufacturing alternating current from the direct current in the event of a failure of the alternating current. 10

27. In a signal system for railroads, in combination, a stretch of track divided into track sections, a signal located at the entrance of each track section having two indicators, an operating mechanism for each indicator, a source of alternating current and a source of direct current at each signal, one pair of conductors only for interconnecting adjacent signals, means for controlling said signals by applying alternating current 15 and direct current to said one pair of conductors in accordance with traffic conditions ahead, and automatic means for obtaining alternating current from the direct current source in the event of a failure of the alternating current source. 20

28. In a signal system for railroads, in combination, a stretch of track divided into track sections, a signal located at the entrance of each track section having two indicators, an operating mechanism for each indicator, a source of alternating current and a source of direct current at each signal, one pair of conductors only for interconnecting adjacent signals, means for controlling said signals by applying alternating current 25 and direct current to said one pair of conductors in accordance with traffic conditions ahead, and automatic means for obtaining alternating current from the direct current source in the event of a failure of the alternating current source. 30

29. In a signal system for railroads, in combination, a stretch of track divided into track sections, a signal located at the entrance of each track section having two indicators, an operating mechanism for each indicator, a source of alternating current and a source of direct current at each signal, one pair of conductors only for interconnecting adjacent signals, means for controlling said signals by applying alternating current 35 and direct current to said one pair of conductors in accordance with traffic conditions ahead, and automatic means for obtaining alternating current from the direct current source in the event of a failure of the alternating current source. 35
